UNITED STATES PATENT OFFICE

2,607,507

WALLPAPER AFFIXING DEVICE

Arthur C. Smith, Arlington, Va., assignor of one-half to La Viella T. Harris, Bethesda, Md.

Application February 1, 1951, Serial No. 208,884

5 Claims. (Cl. 216—7)

1

This invention relates to a wall paper affixing device.

In the hanging of wall paper considerable maneuvering and effort is required to apply the wall paper to portions of room wall surfaces to which access is difficult by virtue of some permanent obstruction like a radiator, wall supported brackets, and the like, being contiguous to such portions. The wall paper is usually applied to these non-readily accessible portions of room wall surfaces by inserting the wall paper sheet between the radiator and the adjacent wall surface with the pasted face of the sheet facing the wall surface and then pressing against the other face of the sheet adjacent one end thereof by hand to cause adherence of the portion of the pasted face adjacent such one end to the contiguous portion of the wall surface. The remainder of the pasted wall paper sheet is then made to adhere to the adjacent portion of the wall surface by forcibly wiping a ruler or like stick over the other or ornamental face of the sheet from the attached one end of the sheet to the other end thereof. This manner of application has the disadvantages in that the wiping pressure is unevenly applied over the entire area of the sheet, and the ornamental face of the sheet is marred, resulting in the appearance of bulges and cracks with unsightly demarcations.

An object of the present invention is to provide a wall paper affixing device which is capable of applying wall paper to non-readily accessible wall portions evenly and with precision and certainty.

Another object of the present invention is to provide a wall paper affixing device which is susceptible of ready accommodation to non-readily accessible wall room portions.

A further object of the present invention is to provide a wall paper affixing device which is simple in structure, and commercially feasible.

Other objects and features of novelty will be apparent from the description taken in conjunction with the drawings in which.

Figure 1 is a perspective view, with parts broken away and in section, of the wall paper affixing device of the present invention with the handle attached to the support intermediate its ends.

Figure 2 is a sectional view taken on the line 2—2 of Figure 1.

Figure 3 is a sectional view taken on the line 3—3 of Figure 1.

Figure 4 is a top plan view of the device of Figure 1 with the handle attached to the end of the support.

2

Figure 5 is a sectional view taken on the line 5—5 of Figure 4.

Figure 6 is a sectional view taken on the line 6—6 of Figure 4.

Figure 7 is a perspective view showing the device of the present invention applied to the ornamental face of a wall paper sheet in the process of being made to adhere to a wall surface portion behind a radiator.

Figure 8 is a fragmentary view of the right hand portion of the device of Figure 1 but with a paper cutter attached to the other end of the support.

Figure 9 is a fragmentary view of the right hand portion of the device of Figure 1 but with a paper roller attached to the other end of the support.

Figure 10 is a fragmentary view of the right hand portion of the device of Figure 1 but with a broad knife attached to the other end of the support.

Referring to the drawings, the numeral 10 designates the wall paper affixing device of the present invention, such device comprising a support or bar 11, and a flexible wiping element or brush 12 arranged longitudinally of said support and connected to said support for movement toward and away from the latter. As shown in Figures 1 and 4, the backing of the flexible wiping element or brush is detachably secured in a backing member 13 which is arranged longitudinally of the support or bar 11, the backing member being connected at one end to one end of the support or bar 11 for movement about an axis 14 transverse of the support 11 toward and away from the latter. Interengaging means are on the wiping element or brush 12 for securing the wiping element in a selected position of its movement toward and away from the support, such means embodying a shackle 15 arranged transversely of and fixedly secured to the backing member 13 adjacent the other end thereof, a threaded bolt 16 fixedly carried by the support or bar 11 adjacent the other end of the latter and having the threaded end projecting beyond the support, the shackle 15 being slidably connected to the bolt 16 by the opposed slots 18 and 19 in the legs of the shackle slidably engaging the shank of the bolt, and a wing nut 17 in threaded engagement with the projecting end of the bolt 16 and rotatable into and out of bearing engagement with the adjacent portion of the leg of the shackle 15 to thereby releasably secure the wiping element or brush 12 in any selected position of its movement with respect to the support.

On one end of the support or bar 11 is a means

or stud 20 which is in longitudinal alignment with said one end and projects from the latter, and on the support or bar intermediate its ends is another means or stud 21 which is positioned transversely of the support and projects from the latter, the respective means or studs 20 and 21 being each for the attachment of one end of a handle 22 thereto. As shown in Figure 5, the one end of the handle 22 is provided with a sleeve 23 which frictionally embraces the stud 20. The other end of the support or bar 11, Figures 4 and 6, is provided with a means or an inwardly extending opening 24 for attachment or receiving a handle of a paper hanger's implement. The implement may be a paper cutter 25 as shown in Figure 8, a paper roller 26 as shown in Figure 9, or a broad knife 27 for use in scraping walls or pointing up plastering and as shown in Figure 10.

With the device of the present invention having the handle 22 attached to the stud 21 of the support 11, as shown in Figure 1, the paper hanger, Figure 7, inserts the device between the radiator 28 and the adjacent wall surface 29 with the handle 22 extending between adjacent radiator sections 30 and 31 and leaning toward him so that the brush 12 will bear against the ornamental face 32 of a wall paper sheet 33 adjacent the attached end 34 of the sheet 33, and while the device is so positioned forcibly wipes the brush 12 over the face 32 from the attached end 34 of the sheet 33 to the other end 35 thereof. This results in the adherence of the sheet 33 to the wall surface 29 evenly throughout the entire area of the sheet.

It is to be understood that where the wall surface to be papered is such that requires the attachment of the handle 22 to the stud 20, the handle is readily slipped off of the stud 21 and slipped on the stud 20. Also, where cutting of the paper sheet, rolling of the pasted sheet or of the meeting edges of attached wall paper sheets, or pointing up or scraping of the wall surface prior to affixation of the wall paper, is required, all that the paper hanger has to do is to attach to the means or opening 24 of the support 11 the respective cutter 25, roller 26, or broad knife 27.

Having thus described the invention what is claimed as new and desired to be secured by Letters Patent is:

1. A wall paper affixing device comprising a support, a flexible wiping element arranged longitudinally of said support and connected to said support for movement toward and away from the latter, interengaging means on said element and said support for securing said element in a selected position of its movement, means in longitudinal alignment with one end of said support and projecting from said one end of said support for attachment of an end of a handle thereto, and a second means positioned transversely of said support intermediate the ends of the latter and projecting from said support for attachment of an end of a handle thereto.

2. A wall paper affixing device comprising a support, a flexible wiping element arranged longitudinally of said support and connected to said support for movement about an axis transverse of said support toward and away from the latter, interengaging means on said element and said support for securing said element in a selected

position of its movement, means in longitudinal alignment with one end of said support and projecting from said one end of said support for attachment of an end of a handle thereto, and a second means positioned transversely of said support intermediate the ends of the latter and projecting from said support for attachment of an end of a handle thereto.

3. A wall paper affixing device comprising a support, a flexible wiping element arranged longitudinally of said support and connected to said support for movement about an axis transverse of said support toward and away from the latter, interengaging means on said element and said support for securing said element in a selected position of its movement, a stud in longitudinal alignment with one end of said support and projecting from said one end of said support for attachment of an end of a handle thereto, and a second stud positioned transversely of said support intermediate the ends of the latter and projecting from said support for attachment of an end of a handle thereto.

4. A wall paper affixing device comprising a support, a backing member arranged longitudinally of said support and connected at one end to one end of said support for movement about an axis transverse of said support toward and away from the latter, a brush arranged longitudinally of said backing member and supported in the latter, interengaging means on said backing member and said support for securing said backing member in a selected position of its movement, a stud in longitudinal alignment with one end of said support and projecting from said one end of said support for attachment of an end of a handle thereto, and a second stud positioned transversely of said support intermediate the ends of the latter and projecting from said support for attachment of an end of a handle thereto.

5. A wall paper affixing device comprising a support, a flexible wiping element arranged longitudinally of said support and connected to said support for movement toward and away from the latter, interengaging means on said element and said support for securing said element in a selected position of its movement, means in longitudinal alignment with one end of said support and projecting from said one end of said support for attachment of an end of a handle thereto, a second means positioned transversely of said support intermediate the ends of the latter and projecting from said support for attachment of an end of a handle thereto, and a third means extending inwardly from the other end of said support for securing of a paper hanger's implement thereto.
